United States Patent

Des. 235,478
Patented June 17, 1975

235,478

MICROSCOPE STAND

John T. Armbruster, Niagara Falls, N.Y., assignor to
American Optical Corporation, Southbridge, Mass.

Filed Mar. 21, 1973, Ser. No. 343,583

Term of patent 14 years

Int. Cl. D16—06

U.S. Cl. D57—1 E

FIG. 1

FIG. 2

FIG. 1 is a perspective view of the microscope stand embodying my new design; and

FIG. 2 is a plan view from one side of the microscope stand.

I claim:

The ornamental design for a microscope stand, as shown and described.
